UNITED STATES PATENT OFFICE

160,853

METAL GLASS SEAL OR SIMILAR ARTICLE

Mannes N. Glickman and Michael Klebanoff,
Nutley, N. J.

Application October 25, 1949, Serial No. 5,696

Term of patent 14 years

(Cl. D26—8)

To all whom it may concern:

Be it known that we, Mannes N. Glickman and Michael Klebanoff, respectively a citizen of the United States, residing at Nutley, New Jersey and a citizen of the United States, residing at Nutley, New Jersey, have invented a new, original, and ornamental Design for Metal Glass Seals or Similar Articles, of which the following is a specification, reference being had to the accompanying drawing, forming part thereof.

In the drawing

Fig. 1 is a front elevational view of a metal glass seal or similar article showing my new design;

Fig. 2 is a top plan view thereof; and

Fig. 3 is a sectional view taken on the line 3—3 of Fig. 2.

We claim:

The ornamental design for a metal glass seal or similar article, as shown.

MANNES N. GLICKMAN.
MICHAEL KLEBANOFF.
